UNITED STATES PATENT OFFICE.

GEORGE W. PRITCHETT, OF GREENSBORO, NORTH CAROLINA.

TAMPING MECHANISM

968,410.

Specification of Letters Patent. Patented Aug. 23, 1910.

Application filed October 26, 1908. Serial No. 459,563.

To all whom it may concern:

Be it known that I, GEORGE W. PRITCHETT, a citizen of the United States, residing at Greensboro, in the county of Guilford and State of North Carolina, have invented certain new and useful Improvements in Tamping Mechanism, of which the following is a specification.

My invention relates to mechanism for tamping roads, fills, and the material employed to refill ditches in roads, and for similar purposes.

One of its objects is to provide simple and efficient power actuated tamping mechanism.

Another object is to provide a portable and self-propelled power actuated tamping mechanism with means for guiding the same.

Another object is to provide tamping mechanism adapted to operate upon ditches and other uneven surfaces.

Another object is to provide means for tamping surfaces of varying widths, and throwing part of the tamping mechanism out of operation as required.

It further consists in certain details of form, combination and arrangement, all of which will be more fully set forth in the description of the accompanying drawings in which:

Figure 1 is a top plan view of my improved tamping mechanism. Fig. 2 is a side elevation of the same, partly in section on line $v-v$ of Fig. 1. Fig. 3 is a front end elevation of the upright frame. Fig. 4 is a perspective view of one of the tamping bars detached.

In the accompanying drawings A represents a vehicle frame having a forward axle a carrying a fifth wheel A' of ordinary construction upon which the forward end of the frame A is supported. The rear end of frame A is supported upon a rear axle a' which is journaled in bearings carried by the frame. Wheels a^2 are journaled upon the ends of the forward axle and wheels a^3 are rigidly secured upon the ends of rear axle a' . A steering handle B connected by a lever mechanism $b b'$ with the forward axle serves to vary the angular adjustment of said axle to steer the vehicle in any desired direction.

C represents a vertical frame carried at the forward end of frame A.

D represents a series of tamping bars pro-

vided at their lower ends with tamping shoes d . The bars D are preferably of rectangular cross section, and are slidably mounted in bearings $c c$ of vertical frame C. The shoes d are preferably detachably connected to the bars D in order that shoes of different weight and various shape may be substituted one for another as desired.

E represents a motor which may be a gas or steam engine or electric motor, or may be operated by hand mounted upon frame A if desired. A shaft F journaled to frame A is driven, preferably by belt G from a pulley g' on the motor shaft.

H represents a shaft journaled to frame A and receiving motion from shaft F by means of gears $g h$ mounted respectively on shafts F H. Shaft H carries a series of eccentrics I to which are attached a series of pawls or bars K by means of eccentric straps k . The free ends of bars K rest upon spools l carried by a cross bar L attached to vertical frame C. The free ends of bars K in their lower position automatically engage teeth d^1 formed in the upper portion of bars D and serve to lift said bars, being automatically disengaged from said teeth when bars D are in the elevated position by reason of the supporting spools l and the action of the eccentrics. The eccentrics I are preferably arranged upon shaft H so as to lift the bars D successively instead of conjointly. Pawls M serve to lock any one of bars D in the raised position when not required in use, the free end of its corresponding bar K then reciprocating over the smooth lower portion of bar D without lifting the bar D. Thus by throwing one or more of the tamping bars out of use the tread of the tamping bars in use may be suited to the width of the ditch or surface to be treated, and readily varied as required.

The vehicle is self propelled by means of a crank arm N journaled upon the rear axle a' and reciprocated by means of an eccentric rod m^1 attached to crank arm N by a pin m^2 and actuated by an eccentric h^1 on the shaft H, to which rod m^1 is attached by means of an eccentric strap m^3 .

N' represents a ratchet wheel rigid on the rear axle which wheel is engaged by a pawl n to rotate the rear axle and slowly propel the vehicle. The pawl n may be thrown to either side of arm N so as to drive the vehicle in either direction.

The length of arms D is such as to per-

mit tamping of material at the bottom of ordinary street excavations, and said bars automatically adjust themselves to rises and falls in the surfaces they are treating. In 5 tamping the material into street excavations the vehicle spans the ditch lengthwise with the vehicle wheels on the street surface at opposite sides of the ditch while the tamping bars and shoes reciprocate to tamp the 10 loose material into the ditch, the operator guiding the vehicle along the street spanning the ditch. If desired shaft F may be dispensed with and power transmitted directly from the motor to shaft H.

15 The tamping mechanism herein illustrated and described may also be advantageously operated by hand power in place of the motor E, by applying one or more hand cranks to either shaft F or shaft H, 20 where motor power is not readily available.

The mechanism herein shown and described is capable of considerable modification without departing from the principle of my invention.

25 Having described my invention, what I claim is.

1. In a mechanism of the character described, a vehicle, a tamping bar slidably mounted in substantially vertical bearings 30 and provided with a series of teeth, a shaft journaled to said vehicle and adapted to be rotated, an eccentric on said shaft, a pawl, an eccentric strap carried by said pawl, said pawl being reciprocated by the 35 movements of said eccentric, the opposite end of said pawl engaging the teeth of said tamping bar through part of each revolution of said shaft, and a rest to support the free end of said pawl and to serve to automatically disengage said pawl from the 40 teeth of the tamping bar at the limit of the upward movement of said pawl.

2. In a mechanism of the character described, a vehicle carrying a motor, a tamping bar slidably mounted in substantially vertical bearings and provided with a series of teeth, a shaft driven by said motor journaled in bearings carried by said vehicle, and carrying an eccentric, a pawl, an 45 eccentric strap carried by said pawl and engaging said eccentric, a stationary support carried by said vehicle to support the free end of said pawl and to automatically disengage said pawl from the teeth of the 50 tamping bar at substantially the limit of the upward movement of the pawl, the free end of said pawl being adapted to engage the teeth of said tamping bar during part of each revolution of said eccentric, and to 55 be automatically disengaged from said teeth by the movements of said pawl.

3. In a mechanism of the character described, a vehicle carrying a motor, a tamp-

ing bar slidably mounted in substantially vertical bearings and provided with a series 65 of teeth, a revolving shaft journaled to said vehicle and driven by said motor, an eccentric on said shaft, a pawl, an eccentric strap carried by said pawl and engaging said eccentric, a support for the forward end of 70 the pawl, whereby the movements of said pawl automatically engage and disengage said teeth.

4. In a mechanism of the character indicated, a vehicle carrying a motor, a tamping bar slidably mounted in substantially vertical bearings and provided with a series 75 of teeth, a shaft driven by said motor journaled in bearings carried by said vehicle, an eccentric carried by said shaft, a pawl, an eccentric strap carried by said pawl and engaging said eccentric, a stationary support carried by said vehicle and supporting said pawl near its free end, the free end of said pawl being adapted to engage 80 the teeth of said tamping bar during a part of each revolution of said eccentric, and to be automatically disengaged from said teeth by the movements of said pawl relative to said support, a ratchet wheel carried by the 85 driving axle of said vehicle, a rocking bar pivotally attached to the driving axle of said vehicle, a pawl carried by said rocking bar and adapted to engage said ratchet wheel, a connecting rod pivotally and detachably connected at one end to said rocking bar, and an eccentric on said motor driven shaft to which the opposite end of 90 said connecting rod is connected to reciprocate said rod.

5. In a mechanism of the character described, a vehicle, a shaft journaled in bearings carried by said vehicle, adapted to be rotated, and provided with a series of eccentrics set to act at different periods of the 105 revolution of said shaft, a series of tamping bars slidably mounted in a row side by side in substantially vertical bearings, and each provided with a series of teeth, a series of pawls, eccentric-straps carried by said pawls 110 to engage the eccentrics carried by said shaft, rigid supports near the free ends of said pawls, the free ends of said pawls being adapted to engage the teeth of said respective bars through part of the revolution of 115 said eccentrics, and to be automatically disengaged from said teeth by the movements of said respective pawls relative to said supports at substantially the limit of the upward strokes of said respective pawls. 120

In testimony whereof I have affixed my signature in presence of two witnesses.

GEORGE W. PRITCHETT.
